UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

SIGNAL MECHANISM.

1,071,922.

Specification of Letters Patent.

Patented Sept. 2, 1913.

Application filed May 11, 1911. Serial No. 626,609.

To all whom it may concern:

Be it known that I, WINTHROP K. HOWE, a citizen of the United States, and resident of the city of Rochester, in the county of 5 Monroe and State of New York, have invented a new and useful Signal Mechanism, of which the following is a specification.

This invention relates to a signal and particularly to a signal which has no counter-weight adapted to return it to danger position, such as the signals ordinarily placed 10 between the tracks of a railway and commonly called dwarf signals.

The object of this invention is to construct a signal of the character described 15 which will not have excessive side strains imparted to the shaft upon which the signal is fastened, by the means used to return the signal to danger position.

20 The invention consists in the means, a practical embodiment of which is herein described, a better understanding of which will be had as the description progresses, when taken in connection with the accompanying drawings, wherein like characters 25 of reference are used to designate like parts and in which:

Figure 1 is a back elevation of the form selected to illustrate the invention. Fig. 2 30 is a cross sectional elevation on the line A—B of Fig. 1, looking in the direction of the arrows. Fig. 3 is a cross sectional view looking in the direction of the arrows *a*, Fig. 1. Fig. 4 is a cross sectional view looking in the direction of the arrows *b*, Fig. 1. Fig. 5 is a back elevation of another structure embodying the invention. Fig. 6 is a detail view.

Construction.—1 designates a plate which 40 is to be bolted by means of bolts inserted in the holes 2, to a case containing a motor and mechanism driven thereby which by suitable connection is attached to shaft 3, so that when the motor is properly actuated, the 45 shaft 3 will be oscillated in the direction of the arrow *c*, Fig. 1, thereby oscillating the semaphore designated as a whole by 4, so that the semaphore will display what is called the "proceed aspect."

50 Attached rigidly to shaft 3 is the member 5 which has pins 6, 7, inserted therein at diametrically opposite points and has a projecting portion 8, adapted when the semaphore is in the normal position to bear

against stop 9; the pins 6 and 7 are of such 55 size that the rods 10 and 11 having eyes in their end, may fit thereover, the rods 10 and 11 extending in the form of the invention illustrated downwardly through a table 12 which serves to restrain the rods from undesired movements; the springs 13 and 14 being placed about the rods, one of the springs, namely, 13, bearing at its upper end 60 against the under-surface of the table 12, the rod 11 having on its lower end a collar 65 15, which has an enlarged shoulder 16 against which the lower end of the spring 13 bears; the collar 15 being pinned by means of pin 17 rigidly to rod 11 and at such a distance from the lower end of the 70 rod 11 that when the projection 8 on the member 5 is against the stop 9, the collar 15 will be just above the upper surface of the table 18. The spring 14 bears at its lower end against a collar 19, which has a 75 projecting shoulder 20, the collar resting upon the lower plate 18, the upper end of the spring 14 bears against a shoulder 21, upon a collar 22, which collar although spring pressed upwardly by the spring 14 is limited 80 in its upward movement by the cotter pin 23, passed through the rod 10. About each of the rods are placed members 24 which simply serve to prevent the springs 13 and 14 from bending out of line with rods 10 85 and 11 when under tension, a cross section of the members 24 being shown by Fig. 6.

The springs 13 and 14 are partially enclosed at their lower ends as shown in Fig. 1, by constructing upstanding members 30, 90 31 and 32 from the lower table 18. These upstanding members are best shown in section in Fig. 4.

Fig. 5, shows the two springs 13 and 14 acting upon rods 10 and 11 to return member 95 5 to a position so that projection 8 rests against stop 9 and in addition two rods 25 and 26 are attached to the pins 7 and 6 and are spring pressed by the springs 28 and 27 in exactly the same manner as are the 100 rods 10 and 11.

Operation.—When a turning movement is imparted to shaft 3 tending to turn it in the direction of arrow *c*, Fig. 1, the member 5, together with semaphore 4, are turned in 105 the direction of the arrow *c*, and by the same movement the rod 10 is pushed downwardly in the direction of the arrow *d*, Fig.

1, which, through cotter pin 23 and collar 22 causes the spring 14 to be compressed against the lower collar 19, and at the same time the rod 11 is moved upwardly and the collar 15 bearing the shoulder 16 is also moved upwardly as it is attached by means of pin 17 to rod 11, thus causing the spring 13 to be compressed against the lower side of the upper table 12, and in the well known 5 manner the mechanism actuating shaft 3 to perform the different functions heretofore described is held in the moved position until such time as it is desired to return the semaphore 4 to the normal position, at which 10 time the force holding the shaft 3 in its moved position is withdrawn, and as is also well understood upon the withdrawing of this force it is desired that the semaphore 4 return to normal position, but on account 15 of the fact that in the situations in which a type of signal such as is described is used, the semaphore 4 cannot be so weighted as to have a bias to the normal position, consequently, the springs 13 and 14 are used 20 which, as soon as the force exerted to move the shaft 3 in the moved position is removed expand, spring 13 acting through shoulder 16 on collar 15, and pin 17 cause rod 11 to be pushed downwardly, tending to carry 25 with it pin 7 thus tending to rotate shaft 3 toward the normal position, at the same time spring 14 acting through shoulder 21 on collar 22 by means of pin 23 causes rod 10 to be pushed upwardly, carrying with it 30 the pin 6, thus also tending to rotate the member 5 toward its normal position.

It will be observed that by using a plurality of springs any side strains upon the bearing are equalized so that there will be 40 no tendency for the shaft 3 to bind in its bearings, thus greatly lessening the liability of the signal "sticking" in the clear position.

It has been found in practice that two 45 springs acting as heretofore described are entirely practicable and so reduce side strains upon the bearings in which shaft 3 revolves, that no difficulty is encountered by reason of "stuck clear" signals, but in a 50 particularly bad situation where the semaphore 4 may be exposed for a very long time to extreme weather, especially when accompanied by low temperature, if the employment of two springs does not secure the 55 desired result, 4 springs may be employed as illustrated by Fig. 5. The use of 4 springs entirely eliminates all unequal strains upon the bearings on which shaft 3 turns, so that an almost ideal structure is obtained for the 60 purpose of returning an unbiased semaphore to normal position after being moved to the clear position.

To be able to change from indication in 65 one quadrant to indication in another without the use of any other parts than already

exist in a signal, is a very desirable requisite. In the mechanism here illustrated such a change can be easily made, for the stop 9 has faces on each side making the same angle with a horizontal line so if the mechanism is arranged to indicate as does the one 70 illustrated in the upper right hand quadrant, or in the lower left hand quadrant, then by removing member 5 from shaft 3, turning the face which is now exposed as 75 shown in Fig. 1 so as to face in the opposite direction and placing the member on shaft 3 so that projection 8 bears against the right hand face 29 of the stop 9, the member 5 will be in a position for the signal to indicate 80 in the lower right or upper left hand quadrant. At the same time pins 6 and 7 must be put through member 5 from the other side and rods 10 and 11 and the mechanism consisting of springs and collars 85 operating therewith must be interchanged. The position of member 5 under such conditions is shown by dotted lines in Fig. 1, the position of the other parts is sufficiently obvious.

Having explained the principle of my invention and having illustrated concrete physical embodiments thereof, and having thoroughly described the same, what I claim as new and desire to secure by Letters Patent, is:

1. In a signal mechanism, a signal, a shaft upon which said signal is rigidly mounted, said shaft adapted for oscillation, a member rigid with said shaft, pins attached to said member at diametrically opposite points, rods connected to said pins, extending from said member substantially parallel to each other, springs surrounding said rods, a rigid table through which both 105 of said rods pass, one of said springs bearing against the side of said table remote from said member, a collar with a projecting shoulder pinned to one of said rods against which the other end of said last 110 mentioned spring rests, a collar on the other rod in proximity to the side of said table remote from said member held by a pin and having a projecting shoulder, the other of said springs bearing against said 115 collar at one end, a second rigid table through which said rods pass, a collar loosely surrounding said other rod and resting against said second table against which the other end of said other spring rests. 120

2. In a signal mechanism, a signal, a shaft upon which said signal is mounted, said shaft adapted for oscillation, a member rigid with said shaft, connecting means attached to said member on each side of the center of the shaft, rods connected to said connecting means, extending from said member substantially parallel to each other, springs surrounding said rods, a rigid table through which one of said rods passes, one of said 130

springs bearing against the side of said table remote from said member, means attached to said rod against which the other end of said last mentioned spring rests, means attached 5 to the other rod, the other of said springs bearing against said means, a second rigid table through which said rods pass, means loosely surrounding said other rod and resting against said second table against which the other end of said other spring rests.
